UNITED STATES PATENT OFFICE.

PHILIP HAYES, OF WAYNETOWN, INDIANA.

TRACE-BUCKLE.

SPECIFICATION forming part of Letters Patent No. 279,382, dated June 12, 1883.

Application filed April 23, 1883. (No model.)

To all whom it may concern:

Be it known that I, PHILIP HAYES, a citizen of the United States, residing at Waynetown, in the county of Montgomery and State 5 of Indiana, have invented certain new and useful Improvements in Trace-Buckles, of which the following is a specification, reference being had therein to the accompanying drawings.

This invention has relation to improvements in that class of buckles used in harness whereby the trace is connected to the pad skirt or girth; and it consists in the novel construction and arrangement of the various parts of which it is composed, all as will be herein- 15 after more fully explained.

The annexed drawings, to which reference is made, fully illustrate my invention, in which—

Figure 1 is a vertical sectional view of my buckle. Fig. 2 is a face view of the same, and 20 Fig. 3 is a cross-sectional view of the buckle.

Referring to the accompanying drawings by letter, A designates the buckle, having curved side bars, *a*, that are formed with depressions *b* in their upper face to admit the pad skirt or 25 girth *c*, and at the forward end the buckle is provided with a cross-bar, *d*, and the rear end with a cross-bar, *e*, that serve to connect the side bars to one another. At the rear end of said buckle the side bars incline forward and 30 upward, and are connected by a cross-bar, *f*, to which is formed a loop, *g*, that is designed to receive the breeching-strap of the harness.

B indicates a broad plate, one end of which is provided with an eye, *h*, that connects with 35 the cross-bar *f*, and thus forming a hinge therefor. Said plate is provided on its under face with a pin or tongue, *j*, (which is arranged in the center between the hinge end and the opposite end thereto,) that enters one of the holes 40 in the trace, and at the same time passes through one of the holes in the pad skirt or girth, thus connecting the parts to one another. The forward or free end of the plate is provided with a transverse groove, *n*, extending 45 from side to side, in which rests the cross-bar *m*, and serves as a keeper for the link *k*, and

in connection with the side flanges, *n' n'*, of the plate the several parts are securely connected, and accidental displacement of the parts is prevented.

It will be observed from the above description, and by reference to the drawings, that the operation of fastening the trace and girth with the buckle and unfastening the same, as well as adjusting trace to different positions, 50 is very simple, as the operator simply moves the two portions of the trace toward one another, thus disengaging the link *k* from the end of the plate B, when the tongue can be withdrawn and the trace adjusted higher or lower on the pad skirt or girth, or the trace can be lengthened or shortened, and when so adjusted the tongue is again inserted in the hole in the trace, also the hole in the girth, after 55 which the trace is drawn taut and the plate B firmly held in place.

It will be noticed that by my construction of the buckle the trace as well as the girth passes in a straight line through the buckle, and the tongue serves to connect the trace with 60 the girth, and therefore the leather cannot be broken or cut, and labor as well as material is saved in the harness.

Having described my invention, what I claim is—

In a trace-buckle, the combination, with the buckle A, provided with depressions *b b* in its side bars, and link *k*, of the hinged plate B, having transverse groove *n*, side flanges, *n' n'*, and provided with the tongue *j* in its center 70 between the hinge end and the opposite free end, which pin is adapted to pass through the trace and girth, whereby said trace, girth, and buckle are secured to one another, as shown and described.

In testimony whereof I affix my signature in presence of two witnesses.

PHILIP HAYES.
